[57] CLAIM

The ornamental design for a front panel for a dehumidifier, as shown and described.

DESCRIPTION

FIG. 1 is a perspective view of a front panel for a dehumidifier embodying my new design;
 FIG. 2 is a top plan view thereof;
 FIG. 3 is a front elevational view thereof;
 FIG. 4 is a side elevational view thereof;
 FIG. 5 is a rear elevational view thereof; and
 FIG. 6 is a bottom plan view thereof.

*Fig. 1.**Fig. 2.**Fig. 3.**Fig. 4.**Fig. 5.**Fig. 6.*
